UNITED STATES PATENT OFFICE.

EDWIN H. BAARE, OF ST. LOUIS, MISSOURI, ASSIGNEE TO WM. J. LEMP BREWING COMPANY, OF ST. LOUIS, MISSOURI, A CORPORATION OF MISSOURI.

LABELING-MACHINE.

No. 830,194.

Specification of Letters Patent.

Patented Sept. 4, 1906.

Application filed July 21, 1905. Serial No. 270,609.

To all whom it may concern.

Be it known that I, EDWIN H. BAARE, a citizen of the United States, residing at the city of St. Louis, State of Missouri, have invented certain new and useful Improvements in Labeling-Machines, of which the following is a specification.

This invention relates to means for affixing labels to bottles by means of adhesives, and has for its object to accomplish this operation automatically by machinery, and particularly in such manner that each label may receive a coating of the adhesive on all parts of its reverse side, and that this may take place irrespective of the shape of the label.

It has heretofore been found difficult, if not impossible, so to apply the adhesive substance to labels that all parts of their surface thus treated will receive such coating. The result of this has been that the labels would begin to peel from the bottles in spots or to blister in spots, which made the whole label subject to easy detachment or defacement by accident or otherwise. This objection has been especially noted in connection with labels of peculiar or irregular shape; but even in the instance of a label of such difficult and irregular shape as that indicated in the drawings, it has been found in the practical operation of my machine that adhesive is applied to all parts of that side of the label intended to be thus coated.

In the accompanying drawings, forming part of this specification, in which like numbers of reference denote like parts wherever they occur, Figure 1 is a front elevation, Fig. 2 is a rear elevation, Figs. 3 and 4 are side elevations on opposite sides, Fig. 5 is a top plan view; and Fig. 6 is a vertical sectional view on the line 6-6, Figs. 1, 2, and 5.

The main frame 1 of the machine consists of certain vertical standards and horizontal cross-pieces 2. The main frame 1 supports in their several positions the various moving parts hereinafter described. The arrows indicate the direction of rotation or movement of each of said moving parts. A common source of power-supply—for instance, the belt 3—directly or indirectly actuates all said moving parts.

The belt 3 drives the band-wheel 4, keyed to the main shaft 5, to which is also fixed the

grooved pulley 6, which drives the grooved pulley 7 by the belt 8, said pulley 7 being fixed to the shaft 9, which rotates the roller 10, said shaft 9 being journaled in the bearings 11 on opposite sides of the receptacle 12 for the adhesive material 13, applied to the labels by the roller 10 in the course of its rotation. As will be obvious, the roller 10 dips into the adhesive material 13 during part of its rotation and is coated therewith during that part of its revolution where it comes into contact with the labels.

The main shaft 5 is journaled in a cross-piece 2 of the main frame 1 and drives a pinion 14, fixed to its inner end. The particular cross-piece 2 just referred to is made of sufficient width and thickness, at least at certain portions thereof, to provide suitable bearings 15 not only for the shaft 5, but also for the shafts 16 and 17, the uses of which will be hereinafter described. The other bearings 15 for the shafts 16 and 17 are to be found in a similar cross-piece 2 at the opposite side of the machine.

The shaft 17 is stationary and hollow, the hub 18 of the wheel 19 encircling same and revolving therearound, the spokes 20 connecting the rim of said wheel 19 to the hub 18. An additional pair of hollow spokes 21 communicate with the interior of the shaft 17 and also with the dies or label-holders 22, which contain a plurality of perforations 23, thereby affording communication between the exterior atmosphere and the interior of the shaft 17 for purposes hereinafter to be described. A slot 17^a is formed circumferentially partially around the wheel of shaft 17 opposite the openings of spokes 21, so that when the wheel 19 is revolved on shaft 17 the slot 17^a opens into the hollow spokes 21 part of the time, while the part of the circumference of shaft 17 opposite said slot 17^a (marked 17^b) acts as a cut-off of communication between the interior shaft 17 and one of the spokes 21 during that part of the travel of die 22 when same is approaching its highest point. The pipe or tube 24 also communicates with the hollow shaft 17 and leads to a fan 25, (illustrated in a conventional manner.) The shaft of the fan 25 may be driven from the same shaft that imparts motion to the belt 3, if desired. The fan 25 creates suction through pipe 24, shaft 17, slot 17^a, spokes

21, and perforations 23, so that when a label is upon one or both of the dies or label-holders 22 said air suction retains it in that position, except after a spoke 21 has passed the slot 17^a, whereby the uncut-away portion of the shaft 17 is caused to block off the air suction from that spoke 21, as clearly shown in Fig. 6. Thus during the major portion of the rotation of the label-carrier 19 air suction takes place through the perforations 23 and a spoke 21. The shaft 17 by means of the slot 17^a therein thus acts as a valve, allowing air suction the greater part of the time, but cutting same off during that part of the rotation of a spoke 21 when the die 22 is nearing the position shown in Figs. 3 and 6, the air suction being cut off at that time in order to facilitate the stripping of the label from the die 22, as hereinafter described.

20 Other means for producing the required pneumatic action may be substituted for said fan.

The pinion 14 meshes with and drives a gear-wheel 26, fixed to the prolongation 18^a of the hub 18 of wheel 19, which is thus caused to rotate around the stationary hollow shaft 17. The rotation of the wheel 19 carries the dies or label-holders 22 successively past the label-stock located in the label-cup 27, the adhesive-applying roller 10, and 30 to the point where the label is stripped from the label-holder 22, which is in a position slightly in advance of the upper label-holder 22 in Figs. 3 and 6. The die 22 and the cup 27 operate as coacting male and female parts when the die 22 in the course of rotation of the wheel 19 has reached such point of its travel that it can enter the cup 27. As the wheel 19 further rotates the die 22 is withdrawn from the cup 27 and passes onto the 40 roller 10. Within the cup 27 is placed a bunch or stack of labels, which rest upon the forwardly-moving disk or plate 28, borne by the threaded rod 29, which passes through the threaded opening 30 in the bottom 31 of the cup 27 and through the opening 32 in the ratchet-wheel 33 (fixed to the rod 29) and through the threaded opening in the strap or bracket 34. The pawl 35 is kept in engagement with the teeth of the ratchet-wheel 33 by the torsion-spring 36 to prevent retrogressive movement of the ratchet 33, 50 and disk 28. The spring-pressed finger 37 is held by the bracket 38 adjacent to the ratchet 33, so as to impinge against the risers of the teeth on the ratchet 33, and thus to rotate the ratchet 33 and rod 29, thereby forcing forward in the cup 27 the forwardly-moving disk 28. As the arms 39, which carry the platen 40, bearing the cup 27, are 60 pivoted at 41 by means of the rod or shaft 42 to the cross-pieces 2, between which said arms are located, and as an oscillating motion is imparted to said arms, platen, and cup, as hereinafter described, the teeth of 65 said ratchet-wheel 33 are brought into con-

tact with said spring-pressed finger 37 at each alternate oscillation of said members, so as to be pushed forward by the finger 37. The oscillation of the arms 39 is so timed and regulated that the cup 27 opens in just the right position and at the right angle to receive each one of the dies 22 when same reaches that point of its rotation where it is opposite the cup 27 and ready to receive from the stock contained in the cup. This allows the die 22 to enter the cup 27 without friction, and the oscillation of the cup 27 immediately after the die 22 has received a label in the same direction as that in which the wheel 19 is rotating allows of the withdrawal of the die 22 from the cup 27 without friction. The oscillation of the arms 39 is produced by the rod 43, which is pivotally eccentrically attached to pin 44^a at 44, and thereby to pinion 14. As the pinion 14 rotates it alternately depresses and raises the rod 43, which is pivoted at 45 to the projection 46 from the arms 39, which oscillates the cup 27 backward and forward, the parts being so proportioned and arranged that the cup 27 moves 90 backward and forward twice during a single rotation of the wheel 19 in order that each die 22 may register with the cup 27 in the course of its rotation.

When the wheel 19 rotates, so as to cause one of the dies 22 to enter the cup 27, the stock of labels within said cup 27 extends from the disk 28 to a position in cup 27 forward of the row of perforations 47 or at least to a point approximately opposite same. When the die 22 enters the cup 27, it compresses the stock of labels, consisting of a large number of individual labels, so as to express the air from between same and drive it out of the cup 27 through the perforations 47 or along the sides of the stock of labels and of die 22. This leaves the stock of labels like a solid block and allows the suction of air through the perforations 23, the hollow spokes 21, slot 17^a, hollow shaft 17, and pipe 24 induced by the fan 25 to separate a single label from the pile constituting the stock, which label is then held by the air suction just referred to upon the dies 22, which are fastened in place in openings 48 by means of screws 49, which pass through the flange 50 of the dies 22 and enter the rim of wheel 19. The joint between the dies 22 and the spokes 21 is made air-tight by threading the ends of the spokes 21 at 51 for the reception of an internally-threaded collar 52, having a flange 53, through which screws 54 pass to bind same tightly to the die 22, suitable packing being interposed between the collar 52 and the die 22, if desired. The other end of the spokes 125 21 is not threaded, but merely inserted deeply in the opening 55 in the hub 18 for the sake of an air-tight communication with the interior of the hollow shaft 17.

When the label has been separated from 130

the stock by the air suction through the perforations 23, as above described, and while said label is being held upon the die 22 or label-holder by said air suction, the rotation of the wheel 19 carries said label from the label-stock holder 27 to the receptacle 12 for the mucilage, gum, or other adhesive material, preferably in fluid form. As the label passes the roller 10 of said adhesive-applier it receives from said roller 10, usually by direct contact therewith, a coating of the adhesive substance on that side of the label which is intended to go next the bottle. To prevent the label from leaving the die 22 while passing the roller 10, a plurality of fingers 56, pivoted to the rod 57, extending from the receptacle 12, serve as guides for the label and prevent the roller 10 from causing same to adhere to it. The roller 10 is preferably formed of rubber or similar material; but the use of such substance is not essential. The receptacle 12 is supported in proper position by the bracket 58, attached to the main frame 1 of the machine. The spring-fingers 56 are socketed in the sleeve 57^a, encircling the rod 57, a projection 57^b depending from said sleeve 57^a, a perforation 57^c through said projection 57^b receiving the shank of the screw 57^d. By means of the coacting threads on the screw 57^d and in the perforation 57^c of projection 57^b when the screw 57^d is turned to the right the projection 57^b is drawn out from the rear wall of receptacle 12, which rotates sleeve 57^a, and thereby presses the fingers 56 more closely in contact with the roller 10, said fingers being fixed to the sleeve 57^a and moving therewith. The reverse movement of the screw 57^d loosens the contact of the fingers 56 with the roller 10 and may remove same from engagement therewith, if desired. The rod 57 has its bearings in lugs 57^e, projecting rearwardly from the receptacle 12.

In the periphery of the wheel 19 (elsewhere denominated the "label-carrier") a plurality of grooves 59 is provided, which grooves extend through the dies 22, as depicted in Figs. 1 and 5. In said grooves 59 steel wires or threads 60 are located, said wires being endless and passing around the grooved pulleys 61, mounted on the rod 62, journaled in opposite sides of the main frame 1. The presence of the wires 60 in the grooves 59 does not at all interfere with the retention of the label on the dies 22 until the die 22 reaches a position slightly beyond that of the upper die in Figs. 3 and 6. At said point the wires 60 leave the label-carrier 19 to follow their course around the grooved pulleys 61. As they are in a position between the label and the rim of the wheel 19 when their direction of travel runs at a tangent to the periphery of the wheel 19, said wires 60 are adapted to strip the label from the label-holding dies 22 as said dies successively reach said point of

tangential departure of said wires 60 from the wheel or label-carrier 19. Not only this, but as the motion of the wheel 19 actuates said endless wires 60 to travel like endless conveyers they serve as a conveyer for each of said labels from the time that the label is stripped from the label-holder 22 on the label-carrier 19, conveying each label individually to the labeling-table 63.

In the labeling-table 63 grooves 64 receive and contain the wires 60. Said table 63 is vertically movable, and each label conveyed by the wires 60 reaches a point immediately above same at a time when said table 63 is at its lower position. The forward movement of the label on the wires 60 is limited by the stationary pins 65, which pass through perforations running from the top to the bottom of the table 63, said pins being mounted on or integral with the cross-bar 66. Also formed integral with said cross-bar 66 and opening vertically are a pair of sleeves 67, in which a pair of vertical standards 68 reciprocate, said standards 68 supporting the table 63, being rigidly attached in any desired manner to the metal plate 69 of the table 63, said plate 69 having on its edge a flange 70, which retains the rubber block or pad 71 in place, thus giving the table 63 a cushion-like character when the bottle 72 rolls upon it just as same is vertically rising.

The vertical movement of the table 63 is produced by a pair of cams 73, revolving with the shaft 16, which is driven by the pinion 14, meshing with the gear 74, fixed to the shaft 16. The standards 68, which reciprocate through the sleeves 67, formed in the hanger 118 from the top cross-pieces 2 of the main frame 1 at their lower ends, are provided with horizontal sleeves 75, through which the cross bar or shaft 76 passes. On the ends of the cross-bar 76 a pair of rollers 77 is mounted. Said rollers 77 ride in the groove 78 on each of the cams 73, and when in the rotation of the cams 73 the rollers 77 strike the shoulders 79 they ride over same, which instantly causes the table 63, borne by the standards 68, to rise, and the same remains in its higher position so long as the rollers 77 ride upon the high part of the cams 73.

Above the table 63 extends the endless conveyer 80, consisting of a flat belt or web traveling over a pair of pulleys 81, journaled by shafts 82 in horizontal strips 83. Bolts 85 pass through the strips 83, said strips 83 being secured thereon by the nuts 84 on their outer ends. The other ends of the bolts 85 are secured in the pair of arms 86, projecting forwardly from the pair of brackets 87, surmounting the main frame 1 of the machine, whereby a firm support for the endless conveyer 80, as well as one conveniently located, is provided. The function of the endless conveyer 80 is to cause the bot-

tle 72 to travel across the labeling-table 63 until same leaves the table 63 and rolls upon the shelf 88, supported by the bracket 89, projecting from the main frame of the machine, a flange 90 on the shelf 88 preventing the bottle 91 from rolling too far. Bottle 91 is the same as bottle 72, but in a more advanced position, bottle 72 being minus the label and bottle 91 having received its label 10 while passing over the table 63.

The travel of the bottle 72 across the table 63 is slightly due to the inclined position of the shelf 92, upon which the bottle 93 is placed and upon which the bottle 92 runs 15 just before beginning to cross table 63; but it is due also to the incline of the tread 94 and push of the riser 94^a of the escapement 95, which is adapted to rotate with the shaft 96, having the sprocket-wheel 97 fixed to its 20 inner end, said sprocket-wheel 97 being driven by the sprocket-chain 98, which receives motion from the sprocket-wheel 99, driven by the shaft 100. The tread 94 of the escapement 95 assumes an inclined position 25 at the time when the bottle 93 has been carried to the position of bottle 72, causing it to roll down the inclined tread 94 and the somewhat less inclined shelf 92 and across the table 63 until it reaches the shelf 30 88, receiving its label on the table 63. In addition, however, to the rolling motion imparted to the bottle 72 by said inclines it is also positively fed forward by the movement of the endless conveyer 80, which 35 serves also as means for pressing the label more tightly upon the bottle as same travels between the conveyer 80 and the table 63 and initial part of the shelf 88. It will be understood in connection with the foregoing 40 description that the vertical upward movement of the table 63 takes place at the very moment when the bottle 72 lands upon said table and that the vertical movement of the table 63 is sufficient to press the bottle 72 45 into engagement with the conveyer 80. At the same time the vertical movement of the table 63 is likewise sufficient to cause the pins 65 to disappear within or below same, so as to leave a free rolling-surface for the 50 bottle 72 across the table 63, said pins 65 being stationary, as hereinabove stated, and passing through perforations in the table 63. The withdrawal through the table 63 of the pins 65 does not affect the label, which has 55 been delivered by wires 60 against and stopped by said pins 65; but the label is left lying on the rubber pad 71 of the table 63, being disengaged from the wires 60 by the upward vertical movement of the table 63, 60 said movement causing the wires 60 to descend to the lowest portion of the grooves 64 in the table 63. This neatly separates the wires 60, which have conveyed the label to that spot, from said label, even if said wires 65 have become slightly sticky from long use.

By this means the label is left in a position exactly in the path of travel of the bottle across the labeling-table and detached from anything that might tend to hold it, and the bottle by gravity --that is to say, by its mere weight--rolling upon the label causes the label to adhere to it and wrap about it, said adhesion being promoted and tightened and the overplus adhesive material expressed by the pressure of the conveyer 80 and pad 71 75 upon the label and bottle. The shelf 92 may be as much elongated as desired, as in Fig. 5, to accommodate as many bottles 93 as it is deemed proper to put in line to be fed by the escapement 95. A slot 101 in the 80 shelf 92 allows the escapement to rotate on shaft 96 and through said slot.

The shaft 96 is journaled at its rear end in bracket 102, projecting from the main frame 1 of the machine, and at its forward end 85 in a similar bracket 103, also projecting from the frame 1, and on its extreme forward end is fixed the sprocket-wheel 97. The shelf 92 is supported by the brackets 102 and 103.

The shaft 100 is journaled in the bracket 90 104, projecting from a cross-piece 2 of the main frame 1 and in the sleeve 105, the gear 106 being fixed to the rear end of the shaft 100. Said gear 106 meshes with the pinion 107 on the end of the shaft 16, which drives 95 said gear 106 and with it the shaft 100 and with that the sprocket-wheel 99, which imparts motion to the sprocket-chain 98 and in turn to the sprocket-wheel 97, shaft 96, and escapement 95.

The large pinion 108 meshes with and drives the small gear 109, fixed to the shaft 110, bearing the sprocket-wheel 111. Thus through the instrumentality of the sprocket-wheel 111, shaft 110, small gear-wheel 109, 115 and large pinion 108 the shaft 16, actuated from the pinion 14 through the gear-wheel 74, drives the sprocket-chain 112 and sprocket-wheel 113, fixed to the shaft 82, to which is fixed the pulley 81, which thereby imparts 110 motion to the endless conveyer 80, as referred to above. The shaft 82, bearing the sprocket-wheel 113, passes through the sleeve 114, supported by a bracket 115, extending from the arm 86 on that side of the machine. The sprocket-wheel 116 is a mere idler suitably journaled. The short shaft 110 has its bearing in bracket 104. Thus it will be seen that by means of an ingenious arrangement of a variety of mechanisms all the moving 120 parts of the machine are actuated from the single main shaft 5, suitably driven, and that the operations of selecting and separating a single label from the stock of labels, gumming same, conveying the gummed label to the labeling-table, and applying same to the bottle are all controlled from and produced by said main shaft 5, and can be automatically performed with no other human intervention except that of an attendant to refill the 130

label-stock holder 27 with labels, pushing the disk 28 back to the bottom of the cup 27 before that is done, and to keep a suitable number of bottles 93 in line behind the escapement 95. In this connection it should be noted that the shelf 88 may be transformed into an inclined run or that an endless conveyer may be connected therewith, so that by either means the bottles 91 will not have to be removed by hand.

It will be observed that the die or label-holder 22 of the label-carrier 19 is of a peculiar shape, that the label-stock holder—namely, the cup 27—is of a like shape, and that the two right-hand wires 60 (looking from the front) are closer together than the other wires are to each other. The shape of the label which has been practically handled and applied to bottles by the use of this machine is like that of the die 22 and cup 27. In order that the parts of the labels on both sides of the indentation 117 may be properly held and conveyed by the wires 60, it is desirable to locate said two right-hand wires close enough together conveniently to accomplish that purpose. With other odd shapes of labels rearrangement of the wires might be found desirable. In general it may be said that many minor variations in the form and arrangement of the several parts may be made without departing from the nature and spirit of any part of my invention.

The operation of the machine is as follows: All parts move in the direction indicated by the arrows. Power from the shaft of the engine having been imparted simultaneously to the shaft of the fan 25 and the band-wheel 4, the fan induces air-suction through the pipe 24, hollow shaft 17, slot 17^a, hollow spokes 21, and perforations 23 in the dies 22. The receptacle 12 for the adhesive material with which the label is to be pasted upon the bottle having been previously filled with such adhesive, preferably in liquid form, the main shaft 5, by means of belt 8 and pulley 7, rotates the roller 10, the label-stock holder 27 having been filled with labels to a point adjacent to or slightly beyond the circumferential line of perforations 47, the disk 28 being at the bottom of the cup 27. With the rotation of the main shaft 5 the pinion 14 drives the gears 26 and 74 and with them the wheel 19 and shaft 16. Around the shaft 17 is driven the wheel or label-carrier 19, which thus successively presents each die or label-holder 22 at the mouth of the cup or label-stock holder 27 and slightly inserts the same therein. For convenience of this insertion and also to enable the label-holder 22 to compress the stock of labels within the cup 27, expressing the air between the labels through the perforations 47 or alongside the pack of labels and to separate the top label from the stock of labels and remove same from the label-stock holder or cup 27 without

the removed label coming in contact with the edges of the cup 27, said cup 27 is given an oscillating movement by alternate depression and elevation of the rod 43, eccentrically connected to the pinion 14. Each time the label-stock holder 27 oscillates upward (or backward) the finger 37 pushes the ratchet-wheel 33 one or more notches forward, which causes the rod 29 to move forward, carrying with it the disk 28 and the remaining stock of labels, so that the topmost member of said stock will always be in the right position in the forward part of the cup 27 to be separated by the pneumatic suction through the perforations 23 in the label-holder 22. The label-holder 22 leaves the cup 27, holding a label thereon, which is thus carried by the further revolution of the wheel or label-carrier 19 until said label comes in contact with the roller 10, where the label receives a coating of adhesive material. The label-carrier 19 thereupon continues its rotation and carries the gummed label to the point where the wires or threads 60 act as a stripping device and themselves assume the function of label-conveyer to carry said label from the wheel 19 to the labeling-table 63, where the label is positioned by the pins 65 then projecting through and above said table 63. Thereupon the table 63 vertically rises, stripping the wires 60 from the underneath side of the label resting on the table 63 and causing the pins 65 to disappear through the table 63 and bringing the table first into a plane with the shelf 92 and later into a higher position, where the bottle 72 is pressed between the table 63 and the conveyer 80, the label being thus caused to adhere tightly to the bottle which is forwarded by the conveyer 80 as bottle 91 to the shelf 88, thence to be removed by hand or an endless conveyer or otherwise, as may be desired. The high position of the table 63 is maintained until the bottle has rolled across same and has reached the shelf 88. Thereupon the table 63 descends to its lowest position, this alternate rising-and-falling movement of the table 63 being produced by the rotation of the cams 73, fixed to the shaft 16, which is driven by the gear 74, meshing with pinion 14. The rollers 77 ride upon the cams 73 and being connected with the standards 68, supporting the table 63, cause said table to rise and fall. The supply of the bottles to the table 63 is regulated and predetermined by the speed of rotation of the escapement 95, which is actuated by the sprocket-wheel 90 on the shaft 100, driven by the pinion 107, mounted on the shaft 16. The conveyer 80 is also actuated by the shaft 16 by means of pinion 108, gear 109, shaft 110, sprocket-wheel 111, sprocket-chain 112, shaft 82, and one of the pulleys 81. It will be understood that all of the moving parts are so proportioned, arranged, and regulated that they move synchronously, so that each shall perform its

function at the proper time to coöperate with any other and all other parts depending thereon. Thus the escapement 95 releases bottles at such periods of time as to allow same to reach the table 63 before it is higher in plane than the shelf 92, so that the bottles may meet with no obstruction in rolling upon said table and so that they may be lifted into engagement with the conveyer 80. The label-holders 22 are so arranged with relation to the other parts that a label is delivered to the labeling-table 63 at a time when the pins 65 project thereabove and when the upward movement of the table 63 will act to strip the label from the wires 69 and also at such a time with relation to the escapement of the bottles that the same will cause the labels to adhere thereto by rolling thereover. In like manner the oscillation of the label-stock holder is so regulated that its opening registers with the approaching die or label-holder 22 and continues in register therewith until an individual label has been secured by the label-holder and until the label-holder 22 has rotated, so as to be withdrawn from the label-stock holder. 27.

While I have shown and described pins 65 as stationary and reciprocating through the table 63, yet pins for a similar purpose might be merely placed over recesses in table 63, said recesses containing springs which normally project the pins 65 above the table 63, so as to stop the labels when brought into contact therewith by the wires 60, but allow of the depression of said pins 65 within said recesses by the mere force of the bottle 72 rolling over same.

Having thus described my said invention, what I claim, and desire to secure by Letters

40 Patent, is—

1. In a labeling-machine, the combination of a label-carrier, wires in connection therewith so arranged as to pass between the main body of said label-carrier and the label carrier thereby, a labeling-table, the wires being arranged to strip the label from the label-carrier at a predetermined point and convey said label to the labeling-table.

2. In a machine of the character described, the combination of a label-stock receptacle, an adhesive-applier, means for carrying a label from the one to the other, a member upon which the bottle to be labeled can roll to pick up the label by the adhesive thereon, and means for carrying said label from said carrier means with the plain side of the label outward to receive the adhesive to said last-mentioned member.

3. In a machine of the character described, the combination of a label-stock receptacle, an adhesive-applier, means for carrying a label from the one to the other, a member upon which the bottle to be labeled can roll to pick up the label by the adhesive thereon, means for carrying said label from said carrier means

to last-mentioned member, and an endless conveyer to forward the bottle and press the label thereon.

4. In a machine of the character described, the combination of a label-stock receptacle, 70 an adhesive-applier, means for carrying a label from the one to the other, a movable member upon which the bottle to be labeled can roll to pick up the label by the adhesive thereon, and means for carrying said label 75 from said carrier means to said last-mentioned member.

5. In a machine of the character described, the combination of a label-stock receptacle, 80 an adhesive-applier, means for carrying a label from the one to the other, a vertically-movable member upon which the bottle to be labeled can roll to pick up the label by the adhesive thereon, and means for carrying said label 85 from said carrier means to said vertically-movable member.

6. In a machine of the character described, the combination of a label-stock receptacle, an adhesive-applier, means for carrying a label from the one to the other, a vertically- 90 movable member upon which the bottle to be labeled can roll to pick up the label by the adhesive thereon, said member being actuated by one or more cams operated from the same shaft that drives the first-mentioned label- 95 carrier, and means for carrying said label from said carrier means to said vertically-movable member.

7. In a machine of the character described, the combination of a label-stock receptacle, 100 an adhesive-applier, means for carrying a label from the one to the other, a vertically-movable member upon which the bottle to be labeled can roll to pick up the label by the adhesive thereon, said member being actuated by one or more cams operated from the same shaft that drives both said label-carriers, and means for carrying said label from 105 said carrier means to said vertically-movable member.

8. In a machine of the character described, the combination of a label-stock receptacle, an adhesive-applier, means for carrying a label from the one to the other, a member upon 115 which the bottle to be labeled can roll to pick up the label by the adhesive thereon, means for carrying said label from said carrier means to said last-mentioned member, and suitable means to receive and stop the rolling bottle after the label is affixed.

9. A rotary label-carrier, a rotary adhesive-applier, means for stripping the gummed label from said label-carrier, a vertically-moving labeling-table, a feed-escapement, a bottle-forwarder, an oscillating label-stock receptacle, and a driving-shaft, all said parts being actuated from said single shaft.

10. In a machine of the character described, the combination of a stationary hollow shaft, a wheel-like label-carrier driven 130

- therearound having hollow spokes, air-passages communicating between the inside of said hollow spokes and the labels upon said label-carrier, means for producing pneumatic action through said air-passages and shaft to retain the labels upon said carrier, a labeling-table, means for conveying the labels from said carrier to said table, and means for bringing the bottles to be labeled into engagement with the labels.
11. In a machine of the character described, the combination of a label-stock holder, a label-carrier, said label-carrier having label-holders thereon, means for causing said label-holders to enter said label-stock holder to remove labels therefrom, said label-carrier containing grooves underneath the attached labels, and wires located in said grooves adapted at a predetermined point to strip the labels from said holders.
12. In a machine of the character described, the combination of a movable labeling-table, a rotary label-carrier, means to convey the label from the latter to the former and an oscillating label-stock holder coöperating with said rotary label-carrier to assist same in removing labels therefrom.
13. In a machine of the character described, the combination of a vertically-movable labeling-table, a rotary label-carrier, means for conveying the label from said label-carrier to said labeling-table, and an oscillating label-stock holder, the latter coöperating with said rotary label-carrier to assist same in removing labels therefrom.
14. In a machine of the character described, the combination of a labeling-table, a rotary label-carrier, means for conveying the label from said label-carrier to said labeling-table, and an oscillating label-stock holder, the latter coöperating with said rotary label-carrier to assist same in removing the labels therefrom, and said rotary label-carrier having label-holders thereon to dip into said label-stock holder.
15. In a machine of the character described, the combination of a rotary label-carrier, a rotary gummer, an oscillating label-stock receptacle, a labeling-table, and means for stripping the gummed labels from the carrier and forwarding same to the labeling-table.
16. In a machine of the character described, the combination of a labeling-table, a rotary label-carrier, and an oscillating label-stock holder, the latter coöperating with said rotary label-carrier to assist same in removing the labels therefrom, and said rotary label-carrier having label-holders thereon to dip into said label-stock holder, said label-carrier being provided with hollow spokes and mounted on a hollow shaft, and communication with said hollow shaft by means of said hollow spokes being established with the stock of labels by means of perforations through

movement of said table, said table having a standard protruding therefrom adapted to engage said cam means, a main frame, and a guide for said standard in connection therewith.

25. In a machine of the character described, the combination of a main frame having a plurality of cross-pieces, a pair of brackets depending therefrom, a cross-bar connecting said brackets, said cross-bar having vertical openings therein, a vertically-movable labeling-table having standards projecting therebeneath and adapted to reciprocate in said vertical openings, and means for imparting vertically-reciprocating movement to said labeling-table.

26. In a machine of the character described, the combination of a label-stock holder, a label-carrier, an adhesive-applier, stripping means, a movable labeling-table, a bottle-escapement, and a bottle-feed, all operated from a single main shaft.

27. In a machine of the character described, the combination of a label-stock holder, a label-carrier, means for pneumatically selecting and withdrawing a single label at a time from said label-stock holder and attaching same to said carrier, an adhesive-applier, stripping means, a movable labeling-table, a bottle-escapement, and a bottle-feed, all operated from a single main shaft.

28. In a machine of the character described, the combination of an oscillating label-stock holder, a label-carrier having grooves therein, and wires located in said grooves and extending beyond said carrier to strip and forward the labels from said carrier.

29. In a machine of the character described, the combination of a label-stock holder, a label-carrier bearing a plurality of label-holders, means for causing said label-holders to enter said label-stock holder to remove labels therefrom, said label-carrier containing grooves which pass, also, through said label-holders underneath the attached labels, and wires located in said grooves adapted at a predetermined point to strip the labels from said holders.

30. In a machine of the character described, the combination of a label-stock holder, a label-carrier bearing a plurality of label-holders, means for causing said label-holders to enter said label-stock holder to remove labels therefrom, said label-carrier containing grooves which pass, also, through said label-holders underneath the attached labels, and wires located in said grooves adapted at a predetermined point to strip the labels from said holders and carry said labels therefrom to the labeling-table.

31. In a machine of the character described, the combination of a label-stock holder, a label-carrier, means for causing said label-carrier to enter said label-stock holder

to remove labels therefrom, said label-carrier containing grooves underneath the attached labels, and wires located in said grooves adapted at a predetermined point to strip the labels from said carrier.

32. In a machine of the character described, a label-carrier bearing a plurality of label-holders, said label-carrier containing grooves which pass also through said label-holders underneath the attached labels, and wires located in said grooves adapted at a predetermined point to strip the labels from said holders.

33. In a machine of the character described, a label-carrier bearing a plurality of label-holders, said label-carrier containing grooves which pass also through said label-holders underneath the attached labels, and wires located in said grooves adapted at a predetermined point to strip the labels from said holders and carry said labels therefrom to the labeling-table.

34. In a machine of the character described, a label-carrier, an independent adhesive-applier, said label-carrier having label-holders thereon containing grooves underneath the attached labels and engaging said labels on the ungummed side, and wires located in said grooves adapted at a predetermined point to strip the labels from said holders.

35. In a machine of the character described, the combination of a labeling-table, a rotary label-carrier, an independent secondary shaft actuating each, and a primary shaft for driving all of said parts.

36. In a machine of the character described, the combination of a labeling-table, a rotary label-carrier, an independent secondary shaft actuating each, an oscillating label-stock holder, and a primary shaft for driving all said parts.

37. In a machine of the character described, the combination of a rotary label-carrier, a labeling-table, and means actuated by said carrier to strip the labels from said carrier and further convey them to said table.

38. In a machine of the character described, the combination of a rotary label-carrier, a labeling-table, and wires actuated by said carrier to strip the labels from said carrier and further convey them to said table.

39. In a machine of the character described, the combination of a main frame and a rotary label-carrier, a rotary adhesive-applier, an oscillating label-stock holder, a movable labeling-table, and a driving-shaft, all said parts being supported by said main frame and being actuated from said single shaft.

40. In a machine of the character described, the combination of a main frame, a rotary label-carrier in connection therewith, a labeling-table also in connection therewith,

- and a constantly-moving oscillating label-stock holder which moves to coöperate with said rotary label-carrier to assist same in removing labels therefrom.
41. In a machine of the character described, the combination of a main frame, a rotary label-carrier in connection therewith, a movable labeling-table, and a constantly-moving oscillating label-stock holder, the latter coöoperating by its movement with said rotary label-carrier to assist same in removing labels therefrom.
42. In a machine of the character described, the combination of a main frame, a rotary label-carrier in connection therewith, a labeling-table, and a constantly-moving oscillating label-stock holder, the latter coöperating by its movement with said rotary label-carrier to assist same in removing labels therefrom.
43. In a machine of the character described, the combination of a horizontal labeling-table and a bottle-conveyer adjacent thereto, said bottle-conveyer having an escapement in connection therewith having a portion to restrain the bottle-supply, another portion adapted during part of its movement to carry a single bottle and during another part of its movement to impel said bottle forward, and a third portion allowing said bottle to descend at an angle from said escapement to said labeling-table.
44. In a machine of the character described, the combination of a main frame, a rotary label-carrier journaled thereon, and a vertically-movable labeling-table also in connection therewith adapted to receive and hold a gummed label thereon and to allow a bottle to roll thereover, whereby the label is caused to adhere to the bottle.
45. In a machine of the character described, the combination of a main frame, a movable labeling-table supported by and movable with relation to same, a label-carrier also supported by said main frame, and label-conveyers traveling with and partially around said label-carrier and across said labeling-table.
46. In a machine of the character described, the combination of a main frame, a movable labeling-table supported by and movable with relation to same, a label-carrier also supported by said main frame, and label-conveyers traveling with and partially around said label-carrier and across said labeling-table, said table by its movement in one direction stripping the label from said conveyers.
47. In a machine of the character described, the combination of a main frame, a movable labeling-table supported by and movable with relation to same, a label-carrier also supported by said main frame, and label-conveyers traveling with and partially around said label-carrier and across said labeling-table, said table being provided with a stripping means in connection therewith for predetermining the placement of the label upon said table.
48. In a machine of the character described, the combination of a main frame, a movable labeling-table supported by and movable with relation to same, a label-carrier also supported by said main frame, label-conveyers traveling with and partially around said label-carrier and across said labeling-table, a pressing means superimposed above said table, and said table, by its vertical rising movement, stripping the label from said conveyers, pressing the label and bottle into engagement with the superimposed pressing means.
49. In a machine of the character described, the combination of a main frame, a movable labeling-table supported by and movable with relation to same, a label-carrier also supported by said main frame, and label-conveyers traveling with and partially around said label-carrier and across said labeling-table, said table being provided with transverse grooves in which said conveyers run.
50. In a machine of the character described, the combination of a vertically-movable labeling-table having perforations therethrough, stationarily-mounted pins passing through said perforations, and means for imparting vertical movement to said table, whereby said pins are withdrawn from protrusion above said table.
51. In a machine of the character described, the combination of a vertically-movable labeling-table having perforations therethrough, stationarily-mounted pins passing through said perforations, means for passing the bottle across said table and means for imparting vertical movement to said table, whereby said pins are withdrawn from protrusion above said table immediately before the passage of the bottle across said table.
52. In a machine of the character described, the combination of a main driving-shaft bearing a pinion on its inner end, a pair of gears driven thereby, a rotary label-carrier driven by the one, and cam means by the other, and a vertically-moving labeling-table actuated by said cams, said label-carrier picking and forwarding labels to said table.
53. In a machine of the character described, the combination of a main driving-shaft bearing a pinion on its inner end, a pair of gears driven thereby, a rotary label-carrier driven by the one, and cam means by the other, and a vertically-moving labeling-table actuated by said cams, the rising movement of said table being timed to occur immediately after the delivery thereon from said label-carrier of a label.
54. In a machine of the character described, the combination of a main driving-

- shaft bearing a pinion on its inner end, a pair of gears driven thereby, a rotary label-carrier driven by the one, and cam means by the other, a vertically-moving labeling-table actuated by said cams, and means for causing the bottles to be labeled to cross said table, the movement of said label-carrier and of said bottle-propeller and the rising movement of said table being so timed that said table rises immediately after a label has been deposited thereon from said label-carrier and just as a bottle is delivered upon same.
55. In a machine of the character described, the combination of a main driving-shaft bearing a pinion on its inner end, a pair of gears driven thereby, a rotary label-carrier driven by the one, and cam means by the other, a vertically-moving labeling-table actuated by said cams, and label-conveying means from said label-carrier to said table.
56. In a machine of the character described, the combination of a rotary label-carrier having means in connection therewith for pneumatically picking and holding labels, an oscillating label-stock holder having means within same to adjust the label-stock relative to the mouth thereof, said adjustment being caused by the actuation of said means by the oscillation of said label-stock holder, and a common source of power for said label-carrier and said label-stock holder.
57. In a machine of the character described, the combination of a main frame, an oscillating label-stock holder pivoted there-to, a rotary label-carrier also journaled in said main frame, one or more grooved pulleys journaled in connection with said main frame, and an endless conveyer passing round said label-carrier and said pulleys and actuated by the former.
58. In a machine of the character described, the combination of a main shaft, a pinion on its inner end, a rotary label-carrier, a gear-wheel in fixed engagement with said rotary carrier driven by said pinion, an oscillating label-stock holder, and a pitman adapted to rock said label-stock holder and eccentrically attached to said pinion.
59. In a machine of the character described, the combination of a rotary label-carrier and a rotary adhesive-applier located adjacent thereto, both of same being suitably driven, and a plurality of spring-fingers attached to a rotatable sleeve interposed between same for causing the carried labels to travel with said label-carrier, and not to adhere to said adhesive-applier.
60. In a machine of the character described, the combination of a rotary label-carrier and a rotary adhesive-applier located adjacent thereto, both of same being suitably driven, and a plurality of adjustably-pivoted spring-fingers interposed between same for causing the carried labels to travel with said label-carrier, and not to adhere to said adhesive-applier.
61. In a machine of the character described, the combination of a movable label-carrier, a movable gummer, a plurality of fingers interposed between same to act as guides for the label, said fingers being borne by a rotatable sleeve having a depending arm fixed thereto, said sleeve being rotatable upon a rod suitably supported, there being a threaded perforation through said depending arm, and a set-screw, the threads of which coat with the threads in said perforations to adjust said fingers with relation to said movable gummer.
62. In a machine of the character described, the combination of a movable labeling-table, means for causing labels to move partly across said table, and label-stopping pins in connection therewith to stop said labels in their said travel, said pins being arranged to disappear below the surface of said table while the bottles pass over same and arranged to reappear after the bottles have passed.
63. In a machine of the character described, the combination of a reciprocating labeling-table, a bottle-feed, a rotary label-carrier, an independent secondary shaft to actuate each, and a primary shaft for driving all of said parts.
64. In a machine of the character described, the combination of a labeling-table, a rotary label-carrier, an independent secondary shaft to actuate each, an oscillating label-stock holder, an endless conveyer for conveying labels from said carrier to said table, and a primary shaft for driving all said parts.
65. In a machine of the character described, the combination of a rotary label-carrier, a labeling-table, and endless conveyers actuated by said carrier to strip the labels from said carrier and convey them therefrom to said table.
66. In a machine of the character described, the combination of a rotary label-carrier and detachable hollow label-holders mounted inside, but projecting through, the periphery thereof.
67. In a machine of the character described, the combination of a rotary label-carrier and detachable hollow bell-shaped label-holders thereon.
68. In a machine of the character described, the combination of a rotary label-carrier and detachable hollow label-holders with flaring mouths thereon.
69. In a machine of the character described, the combination of a wheel-like label-carrier and a removable label-holder thereon having a flange on said holder, said flange coöoperating with the rim of said carrier to retain said holder in place.

70. In a machine of the character described, the combination of a wheel-like label-carrier, label-holders thereon, flanges on said label-holders, and collars on the spokes of said carrier, said holders being retained in place by said collars and said flanges.

71. In a machine of the character described, the combination of a hollow label-holder, a wheel-like label-carrier, having a broken rim, and air-passages consisting of hollow cylinders inserted in openings, provided therefor, in the hub of the wheel, and said air-passages being continued to the periphery of said wheel by attaching said hollow label-holder to said cylinder.

72. In a machine of the character de-

scribed, the combination of a wheel-like label-carrier, a hollow shaft for same, an air-passage from the periphery of said carrier to said shaft, said passage being formed by a hollow cylinder inserted in the hub of said carrier, a collar on said cylinder, and a hollow label-holder extending from said collar through the periphery of said wheel-like carrier.

In testimony whereof I have affixed my signature in presence of two witnesses.

EDWIN H. BAARE.

Witnesses:

M. E. JOHNSON,
GLADYS WALTON.
